(57) **CLAIM**

The ornamental design for an eyeglass and eyeglass components, as shown and described.

DESCRIPTION

FIG. 1 is a front perspective view of the eyeglass and eyeglass components;

FIG. 2 is a front perspective view of the eyeglass and eyeglass components of FIG. 1;

FIG. 3 is a rear perspective view of the eyeglass and eyeglass components of FIG. 1;

FIG. 4 is a left-side elevational view of the eyeglass and eyeglass components of FIG. 1, the right-side elevational view being a mirror image thereof;

FIG. 5 is a top perspective view of the eyeglass and eyeglass components of FIG. 1; and,

FIG. 6 is a bottom perspective view of the eyeglass and eyeglass components of FIG. 1.

Phantom lining, where utilized, is for illustrative purposes only and is not intended to limit the claimed design to the features shown in phantom.
